UNITED STATES PATENT OFFICE.

ALPHONSE F. PIEPER, OF ROCHESTER, NEW YORK.

X-RAY-TUBE SHIELD.

Application filed July 12, 1926. Serial No. 121,839.

This invention relates to X-ray appliances, such as, for example, to those having the X-ray tube adjustably supported so as to be movable into different positions about an object to be treated. It is desirable that accidental contact with the tube and terminals, particularly the high tension end of the tube, be prevented during the operation of the tube in order to avoid dangerous injury from the high tension current supplied to the tube. It is a common practice to provide heat radiating fins upon the high tension anode or terminal of the tube for cooling it. Such fins increase the tendency of the high potential on the anode to break down the surrounding air gap and jump to other parts of the apparatus or to the patient. Various attempts have heretofore been made to shield the high tension section of the tube, so as to prevent contact therewith and jumping of the high potential across the space surrounding the terminal, particularly toward a patient.

An object of this invention is to provide an improved appliance, with which the high tension portion of the tube will be effectively shielded against contact therewith by the patient; with which the tendency of the high potential to break down the air gap surrounding the terminal will be reduced to a minimum; which will not interfere with the radiation of heat from the high tension anode or terminal; and which will be relatively simple, effective, durable and inexpensive.

Various other objects and advantages will be apparent from the following description of an embodiment of the invention, and the novel features will be particularly pointed out hereinafter in connection with the appended claims.

The invention is in the nature of an improvement upon the device disclosed and claimed in the copending application of Oscar H. Pieper et al., Serial No. 751,219, filed November 21, 1924, and resides in certain improvements thereover and details which will be hereinafter more fully described and set forth in the appended claims.

50 In the accompanying drawings:

Fig. 1 is an elevation of dental X-ray apparatus having a shield constructed in accordance with this invention;

Fig. 2 is a side elevation on a larger scale of the X-ray tube of the same, and its guard, a portion of the shell enclosing the high ten-

sion terminal being broken away to illustrate certain details otherwise concealed thereby;

Fig. 3 is a plan of the same;

Fig. 4 is an end elevation of the guard;

Fig. 5 is a sectional elevation of the tube and guard, the section being taken approximately along the line 5—5 of Fig. 3;

Fig. 6 is a sectional elevation of a portion of the guard, with the section taken approximately along the line 6—6 of Fig. 3;

Fig. 7 is a sectional elevation of one end of the guard and the rods to which it is clamped; the section being taken as along the line 7—7 of Fig. 2;

Fig. 8 is a plan of the high tension terminal enclosing shell; and

Fig. 9 is a sectional elevation of a portion of the guard, the section being taken approximately along the line 9—9 of Fig. 5.

In the illustrated embodiment of the invention, an X-ray tube 10 is supported by rings 11 of insulating material which are connected by rods or bolts 12. The rings 11 are in turn supported from a yoke 13, pivotally mounted between the arms of a fork 14, which is in turn hinged to an arm 15. The latter is in turn hinged at 16, to one member 17 of a pair of telescopic arms, the other member of the pair being carried by and extending forwardly from a stand 18 which is provided upon the upper end of a cabinet 19 containing the usual high tension apparatus 20.

The X-ray tube 10 is provided with a rearward extension 21, through which projects endwise the high tension anode or terminal 22, with heat radiation fins 23 upon the projecting portion of the terminal. A split ring 24 of insulating material, whose sections may be connected by screws 25, is fitted over the free end of the extension 21 of the tube and provided with rearwardly extending lugs 26 (see Figs. 2 and 9). A cup-shaped metal shell 27 is passed over the projecting high tension anode or terminal and the heat radiation fins thereon, and at its open end abuts against the split ring 24 and is fitted over and connected to the lugs 26, so as to be supported thereby, separation being prevented by screws 28 (see Fig. 8).

A coil spring 29 fitting over a pin 30 on the inner end face of the cup-shaped shell 27 abuts under compression against the end of the terminal 22 and makes electrical contact therewith. A tongue 31 may be secured

to the shell 27 in any suitable manner, and at its free end may have an aperture 32 for receiving a hook 33 at the free end of the high tension cable or conductor 34 running from 5 the high tension apparatus 20 of the cabinet. The cable or conductor 34 may be supported at intervals by suitable insulators 35 mounted at the ends of suitable struts 36, as usual in such appliances. The metal shell 10 27 thus serves as a medium of connection between the high tension cable and the terminal and anode of the tube, and will at all times have the potential of the anode.

The split ring 24 grips the tube for some 15 distance each side of its split, and may be provided with a cork or other yielding lining 37 along the contact surface to avoid injury to the tube when the ring sections are drawn together. The ring sections may be elsewhere 20 cut away or channeled as at 38 and 39 (see Fig. 6 particularly) so as to provide channels extending into the interior of the shell 27. Such channels permit of the entrance and exit of air passing around the 25 heat radiating fins to cool the same. The shell 27 may also be provided upon one face with a plurality of ventilation openings 40.

A wire guard 41 is connected to the imperforate side or section of the shell 27 by insulation struts or bars 42, such bars being threaded into apertures provided in the lugs 26 that extend rearwardly from the split ring 24 (see Fig. 9). The shell 27 at its open end may be provided with slots 43 for 30 embracing the struts 42. The guard extends forwardly and terminates in a more or less U-shaped cross bar 44, the free ends of the arms of which are provided with channels 45 for fitting against the rods 12 that connect the tube supporting rings 11. Set screws 46 carried by the free ends of the arms of the bar 44 may be engaged with the rods 12, so as to prevent disengagement of the bar 40 44 from those rods and thus provide a support and anchorage for the forward end of the guard 41.

The rings 11 which grip the tube may be adjusted laterally in arcuate arms of the yoke 13, and in order to ground the guard 41 in all of its adjusted positions, the cross bar 44 may be provided with a leaf spring 47, which at its free end carries a contact pin 48 for engagement with a cross bar of the yoke at all adjustable positions of the tube. The yoke 13 is of metal and suitably grounded, and thus the guard 41 which is also of metal will be grounded.

In the use of the apparatus which has just been described the guard 41 effectively prevents contact with the high tension anode of the tube by the patient or operator in the normal use of the tube, and inasmuch as the guard is grounded, contact with the guard by the patient will result in no injury to the patient. The struts 42 serve to keep the rear

end of the guard spaced from the high tension anode of the tube. The metal shell 27 which surrounds the heat radiating fins and the anode will have the same potential as the fins and the anode. The channels 38 and 39 and the apertures 40 permit of a free circulation of air about the anode and its fins for cooling the same.

The section of the shell 27 which is toward the guard and toward the patient is imperforate and smooth, upon its exterior face at least, and therefore, there will be no thin edges or projections extending toward the guard or patient which would increase the tendency for the high potential on the anode and shell to break down and jump the air gap between the shell and guard. The metal shell and the split ring are relatively inexpensive, and effectively reduce the tendency of the high tension current to break down the air gap to the guard. The maximum of safety, and the cooling of the anode are thus obtained at a minimum of expense.

It will be obvious that various changes in the details, which have been herein described and illustrated in order to explain the nature of the invention, may be made by those skilled in the art within the principle and scope of the invention as expressed in the appended claims.

I claim as my invention:

1. In X-ray appliances, an X-ray tube, a support for the same, a guard supported in spaced relation to said tube to prevent manual contact therewith, and a metal shell enclosing, spaced from and connected electrically to the external high tension terminal of said tube, said shell being spaced from the guard and imperforate along its surface adjacent thereto, whereby jumping of the high tension potential from the shell to the guard will be prevented, said shell being apertured along its surface furthest from the guard for ventilating said terminal.

2. In X-ray appliances, an X-ray tube having in one portion, a high tension terminal, a guard disposed in spaced relation to said portion of the tube for preventing mechanical contact with said tube portion, and a metal wall interposed between the guard and said tube portion in spaced relation to said guard, and connected electrically to said terminal, the face of said wall towards the guard being smooth and imperforate, to reduce the tendency of the high potential to jump the gap to said guard.

3. In X-ray appliances, an X-ray tube having in one portion a high tension terminal, a grounded guard disposed in spaced relation to said portion of the tube for preventing mechanical contact with said tube portion, and a metal wall interposed between the guard and said tube portion in spaced relation to said guard, and connected electrically to said terminal, the face of said wall

towards the guard being smooth and imperforate, to reduce the tendency of the high potential to jump the gap to said guard.

4. In X-ray appliances, an X-ray tube having at one end a high tension terminal with heat radiating projections, a ring secured to said end of the tube, and a metal shell having an open end fitting over and secured to the ring and enclosing and electrically connected to said terminal and its projections, said shell being imperforate and smooth upon the face toward the patient, and provided with ventilating apertures upon the face furthest from the patient whereby breaking down of the air gap from the shell towards the patient will be resisted to the maximum.

5. In X-ray appliances, an X-ray tube having at one end a high tension terminal with heat radiating projections, a ring secured to said end of the tube, a metal shell having an open end fitting over and secured to the ring and enclosing and electrically connected to said terminal and its projections, a guard disposed in spaced relation to the shell for preventing mechanical contact therewith, the face of the shell towards the guard being imperforate and smooth, and the portion of the shell away from the guard being provided with ventilating openings.

6. In X-ray appliances, an X-ray tube having at one end a high tension terminal with heat radiating projections, a ring secured to said end of the tube, a metal shell having an open end fitting over and secured to the ring and enclosing and electrically connected to said terminal and its projec-

tions, a grounded guard of electrically conducting material disposed in spaced relation to the shell for preventing mechanical contact therewith, the face of the shell towards the guard being imperforate and smooth, and the portion of the shell away from the guard being provided with ventilating openings.

7. In X-ray appliances, an X-ray tube having at one end a high tension terminal with heat radiating projections, a ring secured to said end of the tube, a metal shell having an open end fitting over and secured to the ring and enclosing and electrically connected to said terminal and its projections, a guard disposed in spaced relation to the shell for preventing mechanical contact therewith, the face of the shell towards the guard being imperforate and smooth, and the portion of the shell away from the guard being provided with ventilating openings,

said ring having a channel from face to face to admit ventilation air to the interior of said shell.

8. In X-ray appliances, an X-ray tube having in one portion a high tension terminal, a grounded guard disposed in spaced relation to said portion of the tube for preventing mechanical contact with said tube portion, and a metal wall interposed between the guard and said tube portion in spaced relation to said guard, the face of said wall towards the guard being smooth and imperforate, to reduce the tendency of the high potential to jump the gap to said guard.

ALPHONSE F. PIEPER.
